UNITED STATES PATENT OFFICE

149,324

DESIGN FOR A THEATRE

Albert R. Walker, Los Angeles, Calif., assignor to Fox West Coast Theatres Corporation, Los Angeles, Calif., a corporation of Delaware

Application September 9, 1946, Serial No. 133,191

Term of patent 14 years

(Cl. D13—1)

To all whom it may concern:

Be it known that I, Albert R. Walker, a citizen of the United States, residing at Los Angeles, in the county of Los Angeles, State of California, have invented a new, original, and ornamental Design for a Theatre, of which the following is a specification, reference being had to the accompanying drawing, forming a part thereof.

Fig. 1 is a front perspective view of a theater showing my new design;

Fig. 2 is a top plan view; and

Fig. 3 is a front elevational view thereof.

The theatre is of the Quonset type in which the side walls are both curved and have the same appearance as that particular one shown, while the rear end side opposite the side corresponding to the entrance is essentially a plain surface.

I claim:

The ornamental design for a theatre, as shown and described.

ALBERT R. WALKER.
